UNITED STATES PATENT OFFICE.

ARTHUR H. MEMMLER, OF SACRAMENTO, CALIFORNIA.

DRAWING FILE HOLDER.

Application filed February 15, 1926. Serial No. 88,215.

This invention relates to holders for sheet fabrics such as drawings, prints, delicate laces etc. In United States Patents Nos. 1,135,310 and 1,165,108 granted to me, I have disclosed a file case and drawing holder for this purpose. In a co-pending application Serial No. 88,214, filed Feb. 15, 1926, I have disclosed an improved file case. The primary object of my invention herein is to provide an improved drawing or similar sheet fabric holder for use with this improved file case.

Drawings or similar sheet fabrics to be stored should be gripped along one edge thereof and hung therefrom in a draped manner. A holder for such fabrics should be adapted to receive the said one edge and to firmly grip the same evenly therealong. It is another object of my invention to provide such a holder wherein one or several fabrics can be received and firmly gripped merely by operating a key at one end of the holder.

In the accompanying drawing I have illustrated one specific embodiment of my invention, but it will be understood that the invention can be otherwise embodied and that the drawing is not to be construed as defining or limiting the scope of the invention, the claims appended to the specification being relied upon for that purpose.

Referring to the figures of the drawing:

Figure 1 is a front elevation of a frame wherein are stored a plurality of holders comprising my present invention.

Figure 2 is an enlarged fragmentary view of one of the holders.

Figure 3 is a cross sectional view therethrough taken on line III—III of Fig. 4.

Figure 4 is a longitudinal sectional view of the left-hand end of a holder, the same being taken on line IV—IV of Fig. 5.

Figure 5 is a cross sectional view taken on line V—V of Fig. 4.

Figure 6 is a front end view of the holder.

In the drawing, 1 indicates a frame hung on a carriage 2 carried by an overhead track 3 supported on the ceiling of a vault 4. The frame is provided with end flanges 5 and 6 between which are supported my improved holders 7 in the position shown in Fig. 1. The construction and use of the frame is

fully disclosed in my said co-pending application.

My improved holder 7 comprises an elongated casing, preferably in the form of a brass cylinder as illustrated. An opening 8 is formed through one side thereof, one edge of the casing adjacent the opening being bent inwardly to form a curved support 9 and a cooperating member 10 being pivoted to the opposite edge of the opening at 11. Drawings or other sheet fabrics to be held are adapted to be gripped between the member 10 and support 9 as illustrated.

Three wedging members 12 are provided within the casing for operating the member 10, two of these members being located near the ends of the casing and the other at the center thereof. Since these three members are identical, a description of one will suffice. One of such members is shown in longitudinal sectional view in Fig. 4 of the drawing and comprises the cooperating parts now to be described.

A pair of spaced supporting members 13 and 14 are secured to the casing by screws 15. A screw 16 extends longitudinally and entirely through the casing, this screw extending loosely through the members 13 and 14 being threaded into the members 14. A plate 17 is mounted in a slot in the members 13 and 14 and has its front edge 18 engaging against the rear of the pivoted member 10. One portion of the rear edge of the plate 17 is notched at 19 to receive the opposite sides of the member 14 and prevent longitudinal movement of the plate. The remaining rear edge of the plate is inclined at 20 in a manner cooperating with a like inclined face on a wedge member 21 slidably mounted in the slot of the member 13 and having a lug 22 engaging in an annular groove 23 in the screw 16. The arrangement is such that rotation of the screw in one direction moves it, and with it the wedge member 21, longitudinally with respect to the plate 17, and forces the plates 17 outwardly against the pivoted member 10 and binds the sheet fabrics tightly between the member 10 and the support 9.

The screw is preferably provided with a squared end 24' adapted to be engaged by a key 24.

The use of my invention is believed to be

obvious. Each holder 7 is adapted to receive and hold several drawings or other sheet fabrics 25. When desiring to bind a drawing or other fabric in the holder, the screw 16 is rotated in a direction to permit the member 10 to pivot away from the support 9. The edge of the drawing is then inserted into the opening 8 between the member 10 and support 9. The screw 16 is therefore rotated by the key 24 to force the member 10 against the support 9 in a manner binding the fabric therebetween. The several holders 7 are supported in the frame 1 in the manner indicated, the drawings hanging from each holder loosely overlapping the holders therebelow and the drawings supported by such holders.

The cylinder 7 not only serves as a holder for the drawings, but also the drawings can be rolled thereon when they are to be carried some distance. The holding of all sheets along the entire edge in the holder is advantageous, inasmuch as smaller sheets are securely held together with wide sheets. My improved means of fastening the drawings in the cylinders is definite and positive and does not depend on a spring-holding device which applies pressure in short spans.

Having thus described my invention, what I claim is:

1. A sheet fabric holder comprising the combination of an elongated casing having an opening through one side thereof adapted to receive sheet fabrics therein, a member extending longitudinally of the opening in the casing and hinged at one of its longitudinal edges to one edge of the opening and having its other edge arranged to cooperate with the other edge of the opening to bind the sheet fabrics therebetween, and means extending through the casing and operated from one end thereof for moving the said member.

2. A sheet fabric holder comprising the combination of an elongated casing having an opening through one side thereof adapted to receive sheet fabrics therein, a member pivotally mounted at one of its longitudinal edges on one edge of the opening and having its other longitudinal edge arranged to cooperate with the other edge of the opening to bind the sheet fabrics therebetween, and means engaging the pivoted member at spaced points and extending through the casing and operated from one end thereof for pivotally moving the member.

3. A sheet fabric holder comprising the combination of an elongated casing having an opening through one side thereof adapted to receive sheet fabrics therein, a member pivotally mounted at one of its longitudinal edges on one edge of the opening and having its other longitudinal edge arranged to cooperate with the other edge of the opening to bind the sheet fabrics therebetween, a

screw extending longitudinally through the casing, and wedge means located at spaced points operated by the screw for moving the said member.

4. A sheet fabric holder comprising the combination of an elongated casing having an opening through one side thereof adapted to receive sheet fabrics therein, a member pivotally mounted on one edge of the opening in a manner to cooperate with the other edge to bind the sheet fabrics therebetween, a screw extending longitudinally through the casing, and a plurality of wedge members relatively spaced along the screw and cooperating therewith and with the pivoted member to move the pivoted member about its pivot when the screw is rotated.

5. A sheet fabric holder comprising the combination of an elongated casing having an opening through one side thereof adapted to receive sheet fabrics therein, a member movably mounted on one edge of the opening in a manner to cooperate with the other edge to bind the sheet fabrics therebetween, a plurality of wedge members mounted in and relatively spaced along the casing for moving the first-mentioned member, and a unitary means operative from one end of the casing and having spaced wedges for operating all the said wedge members in a manner to move the first member to bind or release fabrics placed in the opening.

6. A sheet fabric holder comprising the combination of an elongated casing having an opening through one side thereof adapted to receive sheet fabrics therein, a clamping member movably mounted at one edge of the opening and arranged to cooperate with the other edge of the opening to bind the sheet fabrics therebetween, spaced supporting members arranged in pairs and provided with slots, wedge plates mounted in the slots and each interlocked with one of the members of each pair of supporting members, a screw extending longitudinally of the casing and mounted in the supporting members and having a threaded engagement with said one of the pairs of same and provided with annular grooves and wedge members engaging the wedge plates and having lugs fitting in the grooves of the said screw and movable longitudinally of the casing by the said screw to actuate the wedge plates and operate the movably mounted clamping member.

7. A sheet fabric holder comprising the combination of an elongated casing having an opening through one side thereof adapted to receive sheet fabrics therein, a clamping member movably mounted at one edge of the opening and arranged to cooperate with the other edge of the opening to bind the sheet fabrics therebetween, spaced supporting members arranged in pairs and fixed to the casing and provided with slots, wedge plates mounted in the slots of the support.

ing members and movable transversely of the casing and arranged to engage the clamping member at spaced points, a screw mounted in said supporting members and having a threaded engagement with certain of the supporting members and movable longitudinally of the casing when rotated, and

wedge members interlocked with the screw and movable longitudinally of the casing with the screw to move the wedge plates 10 outwardly and operate the movably mounted clamping member.

ARTHUR H. MEMMLER.
